UNITED STATES PATENT OFFICE.

CHESTER A. FRICK, OF MUNCIE, INDIANA.

DESIGN FOR A BOTTLE REFRIGERATOR.

Application filed January 10, 1925. Serial No. 11,995. Term of patent 14 years.

To all whom it may concern:

Be it known that I, CHESTER A. FRICK, a citizen of the United States, residing at Muncie, in the county of Delaware and State of Indiana, have invented a new, original, and ornamental Design for Bottle Refrigerator, of which the following is a specification, reference being had to the accompanying drawing, forming a part thereof.

In the drawing, the figure is a perspective

view of a bottle refrigerator showing my design.

I claim:

The ornamental design for a bottle refrigerator as shown.

In witness whereof, I, CHESTER A. FRICK, have hereunto set my hand at Muncie, Indiana, this 6th day of January, A. D. one thousand nine hundred and twenty-five.

CHESTER A. FRICK.
